ROBERT T. COLQUHOUN, OF VANCOUVER, BRITISH COLUMBIA, CANADA.

INTERNAL-COMBUSTION ENGINE.

1,242,148.

Specification of Letters Patent.

Patented Oct. 9, 1917.

Application filed October 13, 1916. Serial No. 125,451.

To all whom it may concern:

Be it known that I, ROBERT T. COLQUHOUN, a citizen of the Dominion of Canada, residing at Vancouver, in the Province of 5 British Columbia, Canada, have invented certain new and useful Improvements in Internal-Combustion Engines, of which the following is a specification.

This invention relates to a means for 10 economizing the gaseous fuel of an internal combustion engine by delivering into the intake manifold to mix with the gas as delivered from the carbureter a proportion of heated aqueous vapor mixed with a proportion 15 of heated air.

The means by which this is accomplished is particularly described in the following specification, reference being made to the drawings by which it is accompanied, in 20 which:

Figure 1 is a side elevation of the intake side of the engine showing the application of the device.

Fig. 2 is an enlarged detail of the stop 25 cock through which the vapor and air are delivered to the intake manifold of the engine, and

Fig. 3 is a cross section of the same on the line 3—3 in Fig. 2.

In these drawings 2 represents the filling 30 aperture of the radiator and 3 the overflow pipe therefrom; 4 is the exhaust manifold of the engine and 5 the intake manifold. At a position 6 on the radiator overflow 35 pipe 3 below the top of the exhaust delivery to the radiator a pipe 7 is connected, which pipe passes upward over the neck of the exhaust delivery to the radiator and along the upper side of the exhaust manifold 4 with 40 which it is in intimate contact, and passes down to a cock 9 secured directly in the intake manifold 5, or to an elbow secured 45 therein.

The attachment of the pipe 7 to the 45 priming cock 9 may be made in any manner that will allow air to be drawn in at the connection to mix with the vapor drawn from the radiator, preferably by socketing the end of the pipe 7, as shown in Fig. 2, 50 into a cupped end of the cock supporting it on wings or feathers 11, so as to leave interspaces 10 through which air may pass or water drain from the bottom one.

Any water condensed in the pipe 7 or carried over from the radiator when it is excessively heated may be trapped at the air

inlet, that is, will drop from the underside aperture 10 instead of passing through the aperture of the priming cock into the intake manifold.

To induce a flow from the radiator to the pipe 7 instead of upward from the lower end of the overflow pipe a small aperture is provided at 12 in the cap of the filling aperture of the radiator.

With this provision aqueous vapor is drawn from the radiator and delivered to the intake manifold of the engine, in a manner that will avoid drawing any water of condensation with it for the delivery pipe 7 being connected to the vertically disposed overflow pipe any water condensing in that pipe will move straight downward rather than be diverted into the pipe 7. Further, this pipe 7 is inclined upward from the 70 overflow pipe that any water that may condense in it will drain backward to the overflow. Therefrom the pipe 7 is in close contact with the exhaust so that the vapor is highly heated before it reaches the cock 9 75 and in the manner of connecting the pipe 7 to the cock 9 provision is made for admission at 10 of hot air for admixture with the vapor. The cock affords a means for regulating the amount of water vapor and air 80 to the requirements of the engine, and once adjusted will not require to be interfered with, as if the engine makes a greater demand on the fuel the stronger vacuum will induce a greater flow of vapor and air in 85 the same manner as it induces a greater flow of gas from the carbureter. Care must be taken that sufficient space be left between the end of the pipe 7 and the aperture of 90 the cock that any water that may condense in the pipe, while the engine is not in use, 95 may drain freely away.

I am aware that previous to my invention aqueous vapor has been withdrawn from the radiator and has been delivered to the intake manifold on the engine side of the carbureter, and that such air has been heated by contact with the exhaust. I am also aware that such aqueous vapor supply has been drawn from the radiator overflow pipe but where this last has been done the withdrawal pipe has been connected so close to the lower end of the overflow pipe that the efficiency of the device has been impaired by drawing cold air from the lower end of the overflow rather than moist vapor from the radiator.

I also claim advantage in the manner of mixing with the highly heated vapor an amount of hot air at the cock 9, which cock being close to the intake manifold is highly heated by such proximity, so that the air admitted is practically as hot as the vapor with which it is to be mixed and condensation is thereby avoided.

In practical use the device is conducive to a high economy in the amount of gaseous fuel used, and being simple in construction and free from coils and easily applied, without alteration of existing parts, an engine can be furnished with it at trifling cost.

Having now particularly described my invention, I hereby declare that what I claim as new and desire to be protected in by Letters Patent, is:

A means for supplying aqueous vapor and air to the intake manifold of an internal

combustion engine, said means comprising a pipe connected to the overflow from the engine radiator at a position nearer the upper than the lower end of that pipe, a cap for the radiator filling aperture having a small aperture to insure a flow from the upper end of the overflow pipe, said pipe from the overflow being carried at a slight upward incline to the exhaust manifold of the engine and along that exhaust in intimate contact with it for a sufficient distance to insure that the vapor in the pipe is heated, and means for connecting the end of this pipe to the intake manifold of the engine with provision for admitting a small quantity of hot air to mix with the vapor, and means for controlling the amount of air and vapor delivered to the intake manifold.

In testimony whereof I affix my signature.

ROBERT T. COLQUHOUN.
